UNITED STATES PATENT OFFICE.

ELMER R. COE, OF WILKINSBURG, PENNSYLVANIA, ASSIGNOR TO THE UNION SWITCH & SIGNAL COMPANY, OF SWISSVALE, PENNSYLVANIA, A CORPORATION OF PENNSYLVANIA.

APPARATUS FOR THE CONTROL OF ELECTRIC MOTORS.

1,217,413.

Specification of Letters Patent. Patented Feb. 27, 1917.

Application filed September 25, 1915. Serial No. 52,691.

To all whom it may concern:

Be it known that I, ELMER R. COE, a citizen of the United States, residing at Wilkinsburg, in the county of Allegheny and 5 State of Pennsylvania, have invented certain new and useful Improvements in Apparatus for the Control of Electric Motors, of which the following is a specification.

My invention relates to apparatus for the 10 control of electric motors.

One object of my invention is to provide means for preventing the operation of an alternating current motor by current of any but a predetermined frequency.

15 I shall describe two forms of apparatus embodying my invention, and shall then point out the novel features thereof in claims.

In the accompanying drawings Figure 1 20 is a perspective view, partly diagrammatic, showing one form of apparatus embodying my invention applied to the motor of a relay, which as here shown forms part of an alternating current signaling system for railroads. Fig. 2 is a diagrammatic view showing a modification of the apparatus shown in Fig. 1 embodying my invention.

Referring to the drawing, reference character M designates an electric motor comprising a rotor 1 and a stator which is diagrammatically represented by field windings f' and f'' . The shaft 2 on which rotor 1 is mounted is vertical and terminates at its upper end in arms 3. Bell cranks 61 of a 25 centrifugal governor G are pivotally mounted in the slotted ends of arms 3 by means of pins 62, so that the bell cranks are free to swing in a vertical plane. A fly ball 60 is attached to one arm of each bell 30 crank and causes it to depend vertically from its point of suspension when the motor is standing still. The end of the other arm of each bell crank is ball shaped and is inserted in a hole 63 through a sleeve 64 fitting 35 loosely over a rod 4. The lower end of rod 4 is inserted into a vertical hole 67 in shaft 2 and fits loosely therein so that shaft 2 can rotate with respect to the rod. The upper end of rod 4 is bifurcated and pin-connected 40 to an arm 6 riveted to a bracket 7 mounted on pivots 8. A plurality of contacts are usually mounted on the bracket, but to simplify the drawing, I have shown only one contact c comprising a flexible contact finger 45 10 fixed at one end to the bracket 7 by means

of insulated studs 9. The other end of finger 10 is provided with contact tips 11 and 12 adapted to engage stationary contact points 13 and 14 respectively. A flexible wire 10^a leads to contact finger 10, so that contact c 50 may be used to control a circuit connected to wire 10^a and the stationary contact points 13 and 14—as is well known to those skilled in the art.

When the relay is deenergized, contact 65 12—14 is held closed by means of a weight W adjustably mounted on a screw 15 riveted to bracket 7. When the relay is energized by current in field windings f' f'' , rotor 1 is rotated so that the balls of the governor fly 70 apart. By means of the bell cranks 61, sleeve 64 is moved downwardly, so that it engages a collar 65 integral with rod 4. The rotor is prevented by suitable means from moving vertically upward; consequently, 75 rod 4 is pulled downward by means of governor G with a force depending upon the speed of rotation of the rotor. Since the rotor speed varies with the frequency of the current supplied to the motor, it follows 80 that the downward force on rod 4 depends on the frequency of the motor current. The weight W is so adjusted that its biasing force on bracket 7 is not overcome by the downward force on rod 4 until the rotor has 85 accelerated to a speed corresponding to a predetermined frequency, say, 60 cycles. Then bracket 7 is turned counter-clockwise until contact tip 11 engages contact point 13.

The motor is provided with a brake B by 90 means of which the rotor can be quickly retarded, so that when the motor is deenergized and the brake is applied, the upper or front contacts are opened immediately. Brake B comprises a lever arm 21 pivotally 95 mounted near its middle on a shaft 22. One end of lever 21 is provided with a shoe 23 of leather or other frictional material, which shoe is adapted to engage the rim of a disk 24 fixed to rotor 1 by rivets 24^a. A weight 100 W' is adjustably mounted on a screw 26 extending from shaft 22 so that the brake is normally held in the engaging or operative position. Means are provided for removing the brake from the rotor when the stator is 105 supplied with current of sufficient strength and of a predetermined frequency, which means I shall now describe.

Reference character C designates a laminated core comprising two vertical legs 110

and 16^a and two horizontal cross bars 31 and 32. As here shown, cross bar 32 connects legs 16 and 16^a adjacent their lower ends and cross bar 31 joins the said legs adjacent the middle.

A U shaped laminated core 35 is adjustably mounted (by supports not shown on the drawing) adjacent the lower end of core C for purposes which I shall point out below. The upper ends of legs 16 and 16^a terminate in pole pieces 19 and 19'. An armature 20 adapted to bridge these pole pieces is mounted on lever arm 21, so that when the armature is attracted to the pole pieces, as I shall describe hereinafter, lever 21 is turned about shaft 22 so that shoe 23 is raised from disk 24 in opposition to the biasing weight W'. Thus rotor 1 is free to rotate until brake B is again applied by the release of armature 20.

Cross bar 32 of core C is wound with a primary coil 17 connected to a suitable source of alternating current. Cross bar 31 is provided with a secondary coil 18 which is connected in circuit with a condenser 30 and one phase f' of the stator winding. This circuit I shall call the secondary circuit. When alternating current is sent through primary coil 17, an alternating flux is set up through core C, the greatest part of which flows in the low reluctance path comprising cross bar 32, the lower half of leg 16, cross bar 31, and the lower half of leg 16^a. The flux in cross bar 31 induces an alternating electromotive force in secondary coil 18 so that current is caused to flow in the secondary circuit. If both 60 and 25 cycle currents are impressed on the primary 17, currents of both frequencies are induced in the secondary circuit. By proper relative adjustment of the various parts as hereinafter explained, it is possible to make the secondary circuit of high impedance to, say, the 25 cycle current, and resonant to the 60 cycle current. Thus the 25 cycle current is choked down to a negligible value whereas the 60 cycle current is but slightly resisted and therefore is of considerable strength.

To make the secondary circuit resonant to the 60 cycle current I provide the bridge 35 adjacent the core C as shown on the drawing, so that not all of the primary flux passes through the secondary winding 18, but part thereof leaks through the bridge 35. It is well known that a transformer in which part of the primary flux leaks around the secondary coil has a characteristic similar to the characteristic of a transformer having an inductive secondary circuit. Bridge 35 has, therefore, the same effect as an additional inductance connected in the secondary circuit, and may for purpose of discussion be regarded as such. The value of this additional inductance varies accord-

ing to the reluctance of the leakage path. If bridge 35 is moved very close to cross bar 32, the leakage is high and the additional inductance is large, and vice versa. With 60 cycle current in the primary coil the air gap between bridge 35 and core C is adjusted until a condition of resonance is reached, *i. e.*, a condition in which the inductive effect of the leakage flux counterbalances the capacity of reactance of the condenser in the secondary circuit. When this is the case the impedance across the terminals of coil 18 is equal to the comparatively small effective resistance of the secondary circuit, so that for a given voltage across the primary a heavy secondary current is set up. A large current in winding 18 sets up a high counter magneto-motive force, so that part of the primary flux is forced to flow through the upper part of core C. This flux attracts armature 20 to the core C and so raises brake shoe 23 from disk 24. Winding f^2 is supplied, as described hereinafter, from a source of 60 cycle current having proper phase relation to the current in winding f^1 , so that the rotor begins to turn and operates the relay contacts after it has been sufficiently accelerated.

It is evident that the secondary circuit is not resonant to current of any frequency other than 60 cycles; consequently, when 25 cycle current is supplied to primary 17 the secondary impedance is very high and but a negligible amount of current can flow in winding f^1 . At the same time, only a small counter magneto-motive force is set up in cross bar 31, which is not sufficient to force enough flux through armature 20 to attract it to the pole pieces 19. As a result, rotor 1 is not freed by brake B and the relay contacts cannot be operated.

The above described relay is adapted for many uses, for example, as a track relay in an alternating current signaling system for an electrical railroad using alternating propulsion current. Such an application of the relay is shown on the drawing. Reference character R denotes the track rails of a railroad, which rails are divided into blocks by means of insulated joints 50. Only one such block is shown on the drawing. Impedance bonds I are provided to connect electrically the rails of the insulated block with the adjacent rails. Propulsion current is furnished by a 25 cycle alternator A', one terminal of which is connected to a trolley wire L and the other terminal of which is connected to the track rails through one of the impedance bonds I. The propulsion current flows through the two halves of the winding of the impedance bond in opposite directions, so that the core of the bond is not magnetized and offers but little impedance to the flow of the propulsion current. The signaling

current is furnished by a 60 cycle alternator A, which is connected through a transformer T to the track rails at one end of the block. Coil 17 of the relay is connected to the other end of the block. The signaling current flows from transformer T through the track rails to coil 17 provided there is no train in the block. Flow of current from one rail across to the other through the impedance bonds is negligible, for the bonds offer a high impedance to current flowing through the two halves of the winding in one direction, because such current magnetizes the core. The current in coil 17 eventually energizes the winding f' of the relay as hereinbefore explained. Winding f^2 is energized by current from alternator A. Thus current from alternator A reaches both windings f' and f^2 of the relay, provided there is no train in the block. To make these currents of proper phase relation, an adjustable resistance r is connected between generator G and winding f^2 and a variable impedance i is connected between the transformer T and the track rails. The resistance and inductance are adjusted until the signal currents in windings f' and f^2 are displaced from each other, so that motor M is caused to rotate and hold front contact 11-13 closed. This contact controls a signal or other apparatus not shown on the drawing. When a train enters the block its wheels and axles form a low resistance shunt across the track rails so that the signaling current is shunted from coil 17 and therefore from motor winding f' . Then, as explained hereinbefore, brake B is applied so that the rotor speed is immediately lowered and contact 11-13 is opened. When the train leaves the block, potential is again restored to coil 17 so that current is set up in winding f' and brake B is lifted from the rotor. Motor M is thus free to rotate and close contact 11-13 after it has sufficiently accelerated.

It is easily conceived that the 25 cycle current may create a difference of potential across the terminals of coil 17 due to certain causes; such for instance, as unequal bonding of the two lines of rails. This causes a flow of 25 cycle current through coil 17. As explained hereinbefore, this current is choked down to a very small value in winding f' and is unable to operate the brake. Thus the 25 cycle current is prevented from interfering with the normal operation of the relay.

Referring now to Fig. 2, I have here shown the rotor 1 of motor M provided with a brake B', which differs from brake B described for Fig. 1 in the following particulars. Shoe 23 of the brake is mounted in an arm 80 fixed to one end of a shaft 81. The other end of this shaft is secured in a central hole through a Z armature 82. The

weight of arm 80 biases brake B' to an operative position, i. e., a position wherein the brake shoe engages disk 24. To raise the brake shoe from the disk I provide means for turning the Z armature clockwise. As here shown this means is a closed laminated core C' comprising legs 32' and 31' wound with a primary coil 17' and a secondary coil 18' respectively. The secondary coil is connected, as in Fig. 1, in series with a condenser 30 and one stator winding f' of motor M. Midway between legs 32' and 31' are pole pieces P P between which the Z armature 82 is adapted to turn.

The operation of this form of device is similar to the operation explained for the form shown in Fig. 1, and may be briefly described as follows: Coil 17' is connected to sources of alternating currents of a plurality of frequencies, say, 25 and 60 cycle currents. It is desired to make the motor responsive only to the 60 cycle current. The 60 cycle current flowing through coil 17' sets up flux which flows partly through coil 18' and partly through the Z armature 82. The leakage of flux through the Z armature has the same effect as an inductance in the secondary circuit and may be regarded as such for reasons hereinbefore explained. The condenser 30 is of such capacity that at 60 cycles its capacity reactance neutralizes the inductive reactance caused by the leakage flux through the Z armature and the inductive reactance of winding f' . Hence, the secondary circuit is resonant to the 60 cycle current, so that for a given voltage impressed on coil 17' a comparatively heavy current is caused to flow through stator winding f' and secondary coil 18'. The current in coil 18' creates a high counter magneto-motive force in leg 31' of core C' so that a great deal of the flux in the core flows through the path including the Z armature. This causes the armature to turn clockwise so that brake B' is raised off rotor 1. If 60 cycle current of proper phase relation to the current in winding f' is furnished to winding f^2 from a suitable source, the motor will rotate and operate the relay contact (not shown) by turning shaft 2.

When 25 cycle current flows through primary coil 17' it causes 25 cycle flux to be set up in core C'. By far the greater part of this flux flows through leg 31', but it causes only a small 25 cycle current to flow in the secondary circuit, because this circuit offers high impedance to the 25 cycle current. Consequently, coil 18' creates only a small counter magneto-motive force in core 31', so that the 25 cycle flux is not forced to flow through the Z armature in more than negligible quantity. Thus brake B' is not raised off the motor and but little 25 cycle current can reach winding f' . As a result, the motor cannot be operated by the 25

cycle current and the relay contacts remain unaffected.

Although I have herein shown and described only two forms of apparatus embodying my invention it is understood that various changes and modifications may be made therein within the scope of the appended claims without departing from the spirit and scope of my invention.

10 Having thus described my invention, what I claim is:

1. In combination, an alternating current motor, and means controlled by the frequency of the current supplied to said motor for braking the motor.

15 2. In combination, an alternating current motor comprising a member adapted to rotate, and means controlled by the frequency of the current supplied to said motor for 20 braking said member.

25 3. In combination, an alternating current motor, braking means for said motor, and means responsive to a predetermined frequency of current supplied said motor for controlling said braking means.

30 4. In combination, an alternating current motor, braking means for said motor, and means responsive to the frequency of current supplied said motor for controlling said braking means.

35 5. In combination, an alternating current motor, braking means for said motor adapted normally to oppose the motor, and means responsive to the frequency of the current supplied to said motor for rendering said braking means ineffective to oppose the motor.

40 6. In combination, an alternating current motor, braking means for said motor, a circuit for energizing said motor, means for rendering said circuit resonant to alternating current of one frequency, and means controlled by the value of the current in said circuit for governing the braking means.

45 7. In combination, an alternating current motor, a transformer whose secondary supplies current to a winding of said motor, means for rendering said transformer resonant to current of a predetermined frequency and of high impedance to currents of other frequencies whereby all current but that of said predetermined frequency is choked down to a negligible value, a brake for said motor, and means controlled by current of said predetermined frequency for governing said brake.

50 8. In combination, an alternating current motor, normally active mechanical braking means tending to oppose operation of said motor, and means responsive to current of a predetermined frequency supplied to said motor for releasing said braking means.

55 9. In combination, an alternating current motor, a circuit for energizing a winding thereof, said circuit including a condenser,

and a transformer having a secondary connected with said circuit and a magnetic leakage path around the primary whereby said circuit is resonant to current of one frequency supplied to the primary of the transformer but not to current of a substantially different frequency.

10. In combination, an alternating current motor, a magnetizable core comprising a closed path, a primary coil on said core in which currents of different frequencies are present at times, a secondary coil on said core, a circuit including said secondary coil for energizing a winding of said motor, means for rendering said circuit resonant to current of a predetermined frequency, said core comprising also an open magnetic path for shunting part of the flux set up by current in the primary coil when current of the predetermined frequency is flowing in the secondary circuit, an armature in said open magnetic path and controlled by the flux in said latter path, and a brake for the motor controlled by said armature.

11. In combination, an alternating current motor, a magnetizable core comprising a closed path, a primary coil on said core in which currents of different frequencies are present at times, a secondary coil on said core, a circuit including said secondary coil for energizing a winding of said motor, means for rendering said circuit resonant to current of a predetermined frequency so that said secondary coil creates a high opposing magneto-motive force with current of said predetermined frequency, a shunt magnetic path around that portion of said core which is enveloped by said secondary coil and through which a portion of the flux passes when said high opposing magneto-motive force is created, an armature in said shunt path and controlled by the flux in said latter path, and a brake for the motor controlled by said armature.

12. In combination, an alternating current motor, a magnetizable core comprising a closed path, a primary coil on said core in which currents of different frequencies are present at times, a secondary coil on said core, a circuit including said secondary coil for energizing a winding of said motor, means for rendering said circuit resonant to current of a predetermined frequency so that said secondary coil creates a high opposing magneto-motive force with current of said predetermined frequency, a shunt magnetic path around that portion of said core which is enveloped by said secondary coil and through which a portion of the flux passes when said high opposing magneto-motive force is created, and a brake for the motor controlled by flux in said shunt path.

13. In combination, an alternating current motor, a magnetizable core comprising a closed path, a primary coil on said core in

which currents of different frequencies are present at times, a secondary coil on said core, a circuit including said secondary coil for energizing a winding of said motor, 5 means for rendering said circuit resonant to current of a predetermined frequency so that said secondary coil creates a high opposing magneto-motive force with current of said predetermined frequency, a shunt magnetic path around that portion of said core which 10 is enveloped by said secondary coil and

through which a portion of the flux passes when said high opposing magneto-motive force is created, and a **Z** armature in said shunt magnetic path and a brake for the 15 motor controlled by said **Z** armature.

In testimony whereof I affix my signature in presence of two witnesses.
